Patented Oct. 7, 1913.

UNITED STATES PATENT OFFICE.

CARLETON SAWYER, OF FOXBORO, MASSACHUSETTS.

RECTAL IRRIGATOR.

1,074,818.

Specification of Letters Patent.

Patented Oct. 7, 1913.

Application filed November 25, 1908, Serial No. 464,368. Renewed February 27, 1913. Serial No. 751,184.

To all whom it may concern:

Be it known that I, CARLETON SAWYER, a citizen of the United States, residing at Foxboro, county of Norfolk, State of Massachusetts, have invented an Improvement in Rectal Irrigators, of which the following description, in connection with the accompanying drawing, is a specification, like letters on the drawing representing like parts.

This invention has for its object the production of novel, simple and efficient apparatus whereby oil injections can be administered in a cleanly, safe and easily controlled manner without the use of piston syringes, and whereby the objectionable features usually attendant upon rectal oil irrigations are wholly obviated.

The so-called "fountain" type of syringe is at the present time probably the most easily managed and readily controlled form of irrigating apparatus, but its use with oil is highly objectionable on account of the deteriorating action of the oil upon the rubber, and the very practical difficulty of cleansing after such use.

Piston syringes, whether of hard rubber, glass or metal are objectionable for various reasons, principally because of the difficulty experienced in properly controlling their action.

In my present invention I have devised an apparatus for rectal irrigation particularly adapted for use in connection with oil, or oleaginous liquids, which can be used in connection with a "fountain" syringe but without any possibility of the oil or other irrigating liquid coming in contact therewith, and in carrying out my invention I make use of the principle of the displacement of one liquid by another, thereby dispensing absolutely with pistons or similar devices.

The various novel features of my invention will be fully described in the subjoined specification and particularly pointed out in the following claims.

Figure 1 is a view in side elevation of an irrigating apparatus embodying one form of my invention, in readiness for use; Fig. 2 is an enlarged sectional detail of the fitting for the reservoir or holder which contains the irrigating liquid, showing the outlet therefor and the inlet for the displacing liquid.

In my invention I take advantage of the relative specific gravities of oil and water, and so construct the apparatus that the oil

is forced from a suitable reservoir or holder by an incoming body of water.

Referring to the drawings, the oil reservoir or holder is preferably an elongated glass bottle 1 of suitable dimensions to be conveniently handled and to hold the required quantity of irrigating liquid, the filling opening or mouth 2 of the holder when in use being closed by a tight fitting, tubular stopper 3 having a globular head 4. A long outlet tube or conduit 5 passes through the stopper head 4 and its inner end extends nearly to the bottom of the holder 1, see Fig. 1, the outer end of said tube projecting beyond the head 4, as at 6, and is preferably bent laterally, as at 7. The fitting comprising the stopper and its head, and the inlet and outlet ducts or tubes may be made of glass or metal, as most convenient, the head 4 having a bent inlet tube or duct 8 leading thereto, as shown.

In Fig. 2 the arrows show the direction of the incoming and outgoing liquids, and in practice the irrigating nozzle 9 is connected by a length of flexible tubing 10 with the end 7 of the outlet conduit, and a controlling valve 11 of common form may be applied to the tubing. The latter can be renewed from time to time as it is deteriorated by contact with the oil, and is of small cost. Any suitable source of water supply may be connected with the inlet conduit 8, and the most convenient way is to attach to such conduit the end of the tube 12 leading from the bag 13 of an ordinary "fountain" syringe, as shown in Fig. 1, the tube having the usual controlling valve 14 to regulate the flow of water into the holder 1.

To use the apparatus the holder is inverted from the position shown, the stopper 3 is removed and the desired quantity of oil introduced to the holder, after which the stopper is replaced tightly, and the nozzle and water supply connections being in place the holder is turned up into the position shown in Fig. 1, the level of the oil being indicated at 15, normally below the mouth of the conduit 5. Now it will be obvious that the oil will fill the tubular stopper and its head 4, but is prevented from passing into the tube 12 by the water from the bag 13, the valve 14 having been opened prior to inversion of the holder 1, and the holder may be moved about without any possibility of the oil escaping until the flow of the water is established. When the valve 11 is opened the

water flows into the holder through the stopper 3 and displaces the oil, the latter rising in the holder until it overflows into the long part 5 of the outlet conduit and passes thence through the outer part 6 and 7 to the tube 10 and out through the nozzle. As the water is heavier than the oil the latter is lifted and gradually displaced by the incoming water until all, or as much as desired of the charge of oil in the holder has been discharged, whereupon the valve 11 is closed, the apparatus removed and the tube 12 detached. The rest of the apparatus is then emptied and cleaned by boiling or otherwise, as may be necessary.

It will be observed that the apparatus is perfectly clean in use, is at all times under the perfect control of the operator, and the simplicity of the construction enables it to be easily and quickly cleaned after use.

By means of my invention the ordinary rubber bag syringe can be used in connection therewith for oil irrigation without any danger of the oil coming in contact with the rubber, and the use of pistons, compression bulbs and other similar apparatus is obviated.

Having fully described my invention, what I claim as new and desire to secure by Letters Patent is:—

1. In apparatus of the class described, an invertible oil-holder having a filling opening, a removable tubular stopper closed at

its outer end and adapted to entirely fit the filling opening, an oil outlet conduit passed through the closed outer end of the stopper and extending therethrough into the holder and terminating near the bottom thereof, a nozzle tube connected with the outer end of said conduit, and a source of water supply connected with the tubular stopper externally to the oil-holder and communicating with the interior of the oil-holder by the tubular portion of the stopper surrounding the outlet conduit.

2. In apparatus of the class described, an elongated invertible oil holder having a filling opening, a removable tubular stopper to tightly close the opening and having a globular head, an inlet conduit communicating with the interior of the head and stopper, an oil outlet conduit extended through the head and stopper and terminating within the holder near its bottom, the opposite end of said outlet projecting beyond the head, a nozzle tube connected with said projecting end, and a source of water supply connected with the inlet conduit.

In testimony whereof, I have signed my name to this specification, in the presence of two subscribing witnesses.

CARLETON SAWYER.
